UNITED STATES PATENT OFFICE.

LUISE FREY, OF MUNICH, GERMANY.

WAVING-TONGS.

1,117,021.

Specification of Letters Patent. Patented Nov. 10, 1914.

Application filed August 28, 1913. Serial No. 787,140.

To all whom it may concern:

Be it known that I, LUISE FREY, a citizen of the German Empire, and residing at Munich, Germany, have invented certain new and useful Improvements in Waving-Tongs, of which the following is a specification.

My invention relates to waving-tongs for the hair.

Appliances of a hyperboloidal form for curling the hair are already known, but such appliances have been used only as curling pins, the hair being simply wound around them. The so-called "Marcel waves" cannot however be produced with these appliances.

A primary object of my invention is to provide an appliance for forming in the hair waves of a large variety of forms. To this end, I divide a hyperboloidal tool, preferably of metal, through its axis into two halves, and I pivotally connect them, preferably by attaching them to two legs of an ordinary curling-iron in such manner that when the tongs are closed the two plane inner faces of the halves can clamp the hair between them. When the tongs are rotated about the axis of the conoidal tool that portion of the hair which is not held clamped is wound around the outer surface of the tool.

This rotatable tool can be heated in any desired manner, and enables the strikingly effective so-called Marcel waves to be produced rapidly and with certainty without technical skill being requisite.

One illustrative embodiment of my invention is represented by way of example in the accompanying drawing, wherein:—

Figure 1 is a side elevation of my improved tongs and Fig. 2 a section of the operative tool taken on the line 2—2 of Fig. 1.

Referring to the drawing, the tongs resemble the well-known simple curling tongs in respect to the formation of the arms 1, 2, the joint 3, and the handles 4, 5. The mode of fastening the halves of the tool 6, 7 which I employ for waving is also similar to that in these known tongs, *i. e.* the said tool is riveted or otherwise attached to the upper ends of the arms of the tongs. As may be

seen from Fig. 1 and from the section shown in Fig. 2, the two halves 6, 7 form, when closed, a rotatable tool which in this embodiment is shown as an elongated hyperboloid. A preferable feature of the form employed is that the tool diminishes somewhat in diameter between the two transverse sections of maximum diameter near its ends. The inside faces of both halves are rectilinear planes except for the slight rounding at the edges.

My tongs can be heated in the usual manner over a spirit lamp or in any other desired manner.

The mode of operation of the tongs can be described in a few words. The two inside faces 8, 9 of the halves 6, 7 respectively serve only for gripping and securely holding the hair. On the other hand, the hair after being gripped by the tongs, is waved by being wrapped or wound around the rounded outer surfaces of the two halves. My device does not damage the hair in any way. Owing to the unlimited variety of forms which can be given to the halves 6, 7, any desired form of waves can be produced. According to the dimensions of the halves 6, 7, the waves can without difficulty be either large or small, and each wave can exhibit variations in its height and breadth when a special form is given to the halves 6, 7. Hence with my tongs natural waves and wavy curls of various forms can be obtained, and can be made to produce a general effect which best suits the appearance of the person concerned.

I claim:—

Waving tongs comprising a hyperboloidal tool bisected through its longitudinal axis to form clamping jaws, the two halves being pivotally connected and the inner faces of said jaws being flat with rounded edges.

In testimony whereof, I affix my signature in the presence of two witnesses.

LUISE FREY.
